UNITED STATES PATENT OFFICE.

LEWIS LLEWELLYN EVANS, OF BRIDGEPORT, CONNECTICUT, ASSIGNOR OF ONE-HALF
TO GERALD M. HART, OF WILKES-BARRE, PENNSYLVANIA.

TIMER.

Application filed February 2, 1920. Serial No. 355,830.

To all whom it may concern:

Be it known that I, LEWIS L. EVANS, a citizen of the United States, residing at Bridgeport, in the county of Fairfield and 5 State of Connecticut, have invented certain new and useful Improvements in Timers; and I do declare the following to be a full, clear, and exact description of the invention, such as will enable others skilled in the art 10 to which it appertains to make and use the same.

This invention relates generally to circuit controlling devices, and particularly to timers for internal combustion engines having 15 a number of cylinders fired in succession.

The principal object of the invention is to provide a timer, the construction and arrangement of the contacts being such that a positive and good engagement between them 20 is assured and sparking is reduced to a minimum.

Another object of the invention is to generally improve upon devices of this character by the provision of an extremely simple, strong, durable and inexpensive construction, one of which will be efficient and reliable in operation, and well adapted to the purpose for which it is designed.

With these and other objects in view, the 25 invention consists of the novel features of construction, and the combination and arrangement of parts as will be hereinafter fully described and claimed.

In the accompanying drawings in which 30 similar reference characters designate like parts throughout the several views:

Figure 1 is a rear end view of a timer constructed in accordance with this invention, part of the casing and one of the fixed contacts being in section to show the construction of the same.

Fig. 2 is a transverse sectional view taken on the plane indicated by the line 2—2 of Fig. 1.

Fig. 3 is a detail sectional view of one of the fixed roller contacts.

Fig. 4 is a perspective view of one of the fixed roller contacts, and

Fig. 5 is a similar view of the rotary contact wheel or commutator.

In the embodiment illustrated, the timer shaft of an internal combustion engine having a number of cylinders intended to be fired in succession is shown and indicated by the numeral 1. Fixed to the shaft 1 in

order to rotate with the same is a contact wheel or commutator which may be constructed in several ways, but which preferably consists of a metal hub portion 2 provided intermediate of its ends with a laterally extending flat lug or contact portion 3. This contact portion or lug 3 is of less width than the diameter of the hub portion 2, and has its free end curved and beveled from opposite sides into V-shape. Molded 60 or otherwise formed around the hub portion 2 and contact portion 3 is a body 4 of bakelite or other suitable insulating material. This body 4 is flat and has its outer edge curved circularly to form with the outer edge of the contact portion 3, the circular contact wheel. The periphery of the body 4, like the outer edge of the portion 3 is beveled from opposite sides into a V-shape. It is to be noted that the entire periphery of 65 the wheel is smooth and continuous. In other words, there is no projection or depression on the periphery of the wheel at the junction of the edges of the contact portion 3 and the adjacent edges of the insulating body 4.

Any suitable means may be employed for affixing the contact wheel to the shaft 1, but this is preferably done by providing one end of the hub portion 2 of the latter with 70 opposite notches 5 which receive the ends of a pin 6 inserted transversely through said shaft 1. Additional means, not shown, may be used in securing the wheel to the shaft.

Disposed around and enclosing the contact wheel is a casing 7, a portion of which is of cylindrical shape. This casing 7 is supported in any suitable manner with its cylindrical portion concentric to the wheel and is provided with a radially extending 75 lug 8 of usual construction intended to be so connected that the spark can be advanced or retarded as will be understood. As the means for supporting the casing 7 in position around the contact wheel forms no part 80 of the present invention, such means is not shown.

The casing 7 is preferably constructed of metal and its cylindrical portion is provided with a lining 9 of insulating material. The 105 walls of this cylindrical portion are provided with a number of equally spaced openings having disposed therein insulating bushings 10, the outer ends of which are enlarged and disposed on the exterior 110

of the casing and in contact with the outer side thereof. Extending through apertures arranged in the bushings 10 from the inside of the casing, are bolts 11. Upon the 5 ends of these bolts 11 are threaded nuts 12. The bolts 11 and nuts 12 act in the capacity of binding posts to which the wires leading to the spark plugs of the various cylinders of the engine are intended to be 10 connected.

As shown, the heads of the bolts 11 are disposed upon the interior of the casing and clamped between said heads and the insulating lining 9 are resilient arcuate arms 13. 15 These arms 13 curve inwardly away from the interior of the casing and have their free ends provided with spaced parallel ears 14. Fastened to the ears 14 and extending between the same are short axles or shaft 20 sections 15 upon which are revolvably mounted rollers 16. The rollers 16 are of less width than the distance between the ears 14 so that they may shift longitudinally upon the shaft sections 15. The peripheries of the 25 rollers 16 are provided with V-shaped channels or grooves 17, and they run upon the periphery of the contact wheel. The slope of the walls of the channels or grooves of the rollers is preferably the same as that of 30 the V-shaped faces of the periphery of the wheel.

In operation, the timer shaft is rotated so as to rotate the contact wheel and cause the contact portion 3 to successively engage the 35 rollers 16, thereby closing the circuits to the various spark plugs of the engine in succession, the current passing through the shaft 1, hub portion 2, contact portion 3, and in succession the rollers 16, shaft sections 15, 40 ears 14, arms 13, and terminal members 11.

It is obvious that by constructing the contact wheel with a V-shaped periphery and forming V-shaped grooves or channels in the contact rollers a positive and good engagement of these parts will be assured. 45 It is also to be noted that by reason of the fact that the periphery of the wheel is smooth and continuous especially at the junction of the contact portion in the insulating body, sparking in making and breaking the electrical contact is reduced to a minimum. Any irregularity in running, especially any slight longitudinal shifting 50 of the timer shaft 1 and the contact wheel 55 is compensated for by the slight longitudinal shifting of the rollers. This assures that the engagement of the rollers with the periphery of the wheel is good at all times. In removing the casing 7 and replacing the 60 same, the rollers will yield so as to allow the contact wheel to be disengaged or engaged by the same.

It will be apparent that the coating V-shaped peripheries of the contact rollers and 65 wheel will retain the wheel centered in the

casing, both when the timers are on their timer shafts and when they are separate therefrom. In view of the fact that a number of the timers of the invention will be carried in stock by service stations to be 70 used to replace worn or damaged timers on automobiles, and that it is a great advantage, consequently, that each timer contain no separate or disconnected parts which may become lost, the importance of the preceding statement will be evident. 75

From the foregoing description, taken in connection with the accompanying drawings, the construction, use and operation of the invention will be readily understood 80 without a more extended explanation.

Various changes in form, proportion, and in the minor details of construction may be resorted to without departing from the spirit of the invention as defined in the 85 claims.

What is claimed is:

1. A device of the character described, comprising a casing having an open end adapted to be mounted against an engine, a timer shaft extending into said casing and spaced from the wall thereof, a conducting member fixed upon the timer shaft to rotate therewith, contact members upon said casing, the conducting member and contact members being adapted to have interlocking engagement, and means for allowing the location of engagement of said conducting member with said contact members to shift in said casing in a direction parallel with the direction of length of said timer shaft, whereby any longitudinal shifting of said timer shaft and casing relatively to each other can be compensated for by a corresponding shifting of said location of engagement. 95

2. A device of the character described, comprising a casing having an open end adapted to be mounted against an engine, a timer shaft extending into said casing and spaced from the wall thereof, a wheel fixedly mounted upon said timer shaft, said wheel having a V-shaped periphery and a conducting portion extending from the periphery to its hub, contact arms upon said casing, spaced ears formed at the free ends of said arms, and roller contacts rotatably mounted between said ears to have limited movement in a direction parallel with the direction of length of said timer shaft, said roller contacts provided with V-shaped peripheries adapted to engage the corresponding V-shaped periphery of said wheel, whereby any longitudinal shifting of said timer shaft and wheel can be compensated for by a slight shifting of said roller contacts between said ears. 110 115 120 125

In testimony whereof I have hereunto set my hand.

LEWIS LLEWELLYN EVANS.
